UNITED STATES PATENT OFFICE.

WALTER SEARCY, OF PLACERVILLE, CALIFORNIA.

DETACHABLE FLEXIBLE METAL SHOE-PROTECTOR.

1,318,608.

Specification of Letters Patent. Patented Oct. 14, 1919.

Application filed September 21, 1918. Serial No. 255,156.

To all whom it may concern:

Be it known that I, WALTER SEARCY, a citizen of the United States, residing at Placerville, in the county of Eldorado and State of California, have invented certain new and useful Improvements in Detachable Flexible Metal Shoe-Protectors, of which the following is a specification, reference being had therein to the accompanying drawings.

This invention relates to a detachable flexible metal shoe protector, and has for its object the construction of a shoe protector that is efficient in operation and which is comparatively inexpensive to construct.

Another object of the invention is the construction of a shoe protector comprising a heel portion and a sole portion, each being made up of sections of a peculiar structure, and the heel and sole portions being connected up by a leather top or upper structure.

With these and other objects in view my invention comprises certain novel combinations and arrangements of parts as will be hereinafter specifically described, illustrated in the accompanying drawings and more particularly pointed out in the appended claims.

30 In the drawings:

Figure 1 is a perspective view of an apparatus constructed in accordance with the present invention.

Fig. 2 is a longitudinal sectional view 35 taken through the middle of the apparatus depicted in Fig. 1.

Fig. 3 is an inverted plan view of the apparatus shown in Fig. 1.

Fig. 4 is a sectional view taken on the 40 line 4—4 of Fig. 2.

Fig. 5 is a perspective view of one of the blanks or sections of the sole portion showing the same prior to folding.

Fig. 6 is a sectional view taken on the 45 line 6—6, Fig. 2, looking in the direction of the arrows.

Referring to the drawings by numerals, 1 designates the heel portion of my shoe protector, and 2 the sole portion thereof.

50 The heel portion comprises sections 3 and 4. The section 3 is provided on its back with a pair of tongues 5, which tongues extend through apertures in the contiguous portion of section 4 (Fig. 6) holding sections 3 and 4 together at the back, while the

bottom 6—6 of sections 3 and 4 are provided at their front with overlapping tongues 7 and 8. The tongue 7 is provided with a rivet 9 that is adapted to be placed in any one of the apertures 10; in Fig. 3 60 rivet 9 is in one of the apertures, the position of the rivet being more clearly shown in Fig. 2, thereby holding sections 3 and 4 securely together at their front edges, while their rear portions are held securely by 65 means of the tongues 5 (Figs. 2 and 6).

The front portion 2 of my shoe protector comprises a sole made up of a rear plate 11 and a front plate 12, and preferably a series of intermediate plates 13. The intermediate plates 13 (Fig. 5) are provided near their rear edge 14 with a plurality of aligned, elongated slots or apertures 15, and near their ends 16 with elongated apertures 17, at right angles to apertures 15. Along the 70 front edge 18, of each plate 13, are a plurality of tongues 19 arranged in alignment and adapted to fit in the apertures 15 of the adjoining intermediate plate 13, when the plates are assembled, as clearly shown 75 in Figs. 2 and 3. Apertures 20 are provided for receiving the anti-slipping devices 21, such as headed rivets, or any other suitable anti-slipping means; at 22, Fig. 2, I have shown anti-slipping devices that are 80 not provided with as great points as the members 21, any of which devices may be used at the will of the operator by inserting the common shanks through the apertures 20 of plates 13, in the manner shown clearly 85 in Figs. 2 and 4.

The inner plate 11 is provided with the tongues 19, upon its inner edge, and the outer or toe plate 12 is provided with apertures 15 (Fig. 2) for receiving the tongues 95 19 of the contiguous intermediate plate 13.

All of the plates constituting the sole portion of my apparatus are provided with the apertures 17, and in each aperture is pivotally mounted a side plate 23, inasmuch 100 as the side plate is provided with tongue 24 at its lower end, which tongue extends through one of the side apertures 17. Each side plate is provided with an elongated aperture 25 near its upper edge in which a depending strap portion 26, of the leather side 27 is positioned; there are two leather sides 27 employed in the construction of the upper of my shoe protector and these leather sides are provided with lacing eyelet 110

hooks 28, by means of which the lacing 29 is fastened upon the leather sections or portions 27, closing the same over the shoe of the wearer of my apparatus.

5 Each depending portion 26 is threaded through an aperture 25, and then the extended end is folded back upon the body, as shown in Fig. 4, and a rivet 30 is employed for fastening the depending portion 10 to the side plate 23.

The leather sections 27 are provided at their rear with rearwardly-extending straps 27^a, each of which straps is threaded through an aperture 31, formed upon the section 3 15 or 4 (each section being provided with an aperture 31) and this threaded end of the strap 27 is fastened by rivet 32, as shown.

The forward ends of the sections 3 and 4 are connected to the side plates which are 20 attached to the inner section 11, through the medium of straps 33; one of these straps 33 is fastened at its outer end to the section of the heel, and the other strap at each side, is fastened to an elongated aperture 25 formed at the side of the side plate 23 (Fig. 2). A ring 34 connects the straps 33 at each side, and the rings 34 at both sides of my apparatus are connected by a surrounding band or strap 35, provided with a 30 buckle 35^a.

It will be understood that by loosening the lacing 29, that the user can slip his shoe into the device, and then by raising the strap surrounding band 35, to cause it to rest 35 against the upper portion of the shoe, and the lacing 29 being drawn taut, the entire device can be readily attached to the shoe, affording an excellent protection for the shoe, and at the same time an anti-slipping 40 device is provided so that the user of my improved shoe protectors will not slip on the ice or slip off of slippery surfaces, such as logs in the water, or on icy or wet buildings or scaffold.

45 My apparatus is comparatively light in weight and as it is made of parts, it readily conforms to the contour of the shoe, thereby making it a substantial casing of a flexible

or yieldable type for protecting the shoe against foreign objects.

50

My shoe protectors may be provided with a lining of any suitable material or of any suitable construction to prevent the protector from marring or disfiguring the finish or polish of the boot or shoe upon which it is placed.

55

Other modifications or changes may be made without departing from the spirit or scope of this invention as shall fairly fall within the scope of the appended claims.

60

What I claim is:

1. In a shoe protector, the combination of a sole and heel portion, means connecting said sole and heel portions together, said heel portion comprising a pair of sections, one of said sections provided with tongues and the other section provided with apertures receiving said tongues, said sections provided with flat bottoms having near their front edge horizontal overlapping 70 tongues, one tongue provided with a series of apertures, and the other tongue provided with an aperture adapted to register with the apertures of the first-mentioned tongue, and means positioned in said registering 75 apertures of the tongues for holding the sections of the heel portion in an adjusted position.

65

2. A shoe protector comprising a sole and heel portion, and an upper leather structure attached to said sole and heel portions, said heel portion comprising a pair of sections, said sections provided at their back with a tongue and an aperture structure for holding the same together in an adjusted 85 position, and said sections provided at their inner front ends with overlapping tongues and said tongues provided with means for fastening the same in different adjusted positions, to accommodate it to the size of 90 the heel of a shoe upon which the apparatus is to be positioned.

80

In testimony whereof I hereunto affix my signature.

WALTER SEARCY.

Copies of this patent may be obtained for five cents each, by addressing the "Commissioner of Patents, Washington, D. C."
